US00D921509S

(12) **United States Design Patent** (10) Patent No.: **US D921,509 S**
(45) Date of Patent: **** Jun. 8, 2021**

(54) **SECURITY SYSTEM KEYPAD**

(71) Applicant: **Honeywell International Inc.**, Morris Plains, NJ (US)

(72) Inventors: **Chenghao Wang**, Shanghai (CN); **Kong Lei**, Shanghai (CN); **Zhongwei Ding**, Shanghai (CN); **Matteo Besozzi**, Milan (IT)

(73) Assignee: **HONEYWELL INTERNATIONAL INC.**, Charlotte, NC (US)

(**) Term: **15 Years**

(21) Appl. No.: **29/720,565**

(22) Filed: **Jan. 14, 2020**

(51) LOC (13) Cl. **10-05**

(52) U.S. Cl. USPC **D10/108**

(58) Field of Classification Search USPC D10/108, 106.95, 104.1; D14/307, 371; D18/4.6

See application file for complete search history.

(57) **CLAIM**

The ornamental design for a security system keypad, as shown and described.

DESCRIPTION

FIG. 1 is a perspective view of a first embodiment of a security system keypad;

FIG. 2 is a front side view of the security system keypad of FIG. 1;

FIG. 3 is a left side view of the security system keypad of FIG. 1;

FIG. 4 is a right side view of the security system keypad of FIG. 1;

FIG. 5 is a top side view of the security system keypad of FIG. 1;

FIG. 6 is a bottom side view of the security system keypad of FIG. 1;

FIG. 7 is a perspective view of a second embodiment of a security system keypad;

FIG. 8 is a front side view of the security system keypad of FIG. 7;

FIG. 9 is a left side view of the security system keypad of FIG. 7;

FIG. 10 is a right side view of the security system keypad of FIG. 7;

FIG. 11 is a top side view of the security system keypad of FIG. 7; and,

FIG. 12 is a bottom side view of the security system keypad. The portions illustrated in broken lines on the figures form no part of the claimed design.

1 Claim, 12 Drawing Sheets
